UNITED STATES PATENT OFFICE.

PETER YOUNG, OF WEST CHARLESTON, VERMONT.

END-GATE FOR WAGONS.

SPECIFICATION forming part of Letters Patent No. 259,259, dated June 6, 1882.

Application filed April 8, 1882. (No model.)

To all whom it may concern:

Be it known that I, PETER YOUNG, a citizen of the United States, a resident of West Charleston, in the county of Orleans and State of Vermont, have invented a new and valuable Improvement in End-Gates for Wagons; and I do hereby declare that the following is a full, clear, and exact description of the construction and operation of the same, reference being had 10 to the annexed drawings, making a part of this specification, and to the letters and figures of reference marked thereon.

Figure 1 of the drawings is a representation of a top or plan view of my wagon end-gate, 15 and Fig. 2 is a rear view of the same. Fig. 3 is a detail view.

This invention has relation to end-gates for wagons; and it consists in the construction and novel arrangement of the laterally-hinged 20 sections, their angle-hinges, the overlapping perforated cross-bars, and the catch-staples passing through the perforations or apertures of the cross-bars.

The invention also consists in providing the 25 overlapping cross-bars with spring-latches, which are connected so that both of them can be lifted at the same time; and the invention further consists in combining with the laterally-hinged gate-sections an adjustable rope 30 or chain stop, whereby the aperture made between the gate-sections, when partially opened, can be regulated, all as hereinafter set forth.

In the accompanying drawings, the letter A designates a wagon-bed, having the sides 35 B and bottom C, the rear end of which projects a little beyond the end of the sides, forming a bearing, D, on which the end-gate rests when closed.

The end-gate consists of two lateral sections, 40 E and F, the latter being usually shorter than the former, but provided with horizontal cross-bars or cleat-bars I at or near its upper and lower edges, the projecting ends K whereof extend over the upper and lower portions of 45 the longer section, E, to meet the supplemental short cleat-bars I', with which the section E is provided. When the gate-sections are closed the cleat-bars I and I' abut against each other. Apertures or slot-perforations L are 50 made through the projecting portions K of

the cross-bars I, and catch-staples S, secured to the section E, pass through these apertures and afford means whereby the sections may be fastened together in the closed position. This may be effected by a vertical rod passing 55 through the staples, or by means of spring-latches N, engaging notches made in the heads of the staples, which are formed with inclined upper edges, as indicated at P. In the notched staples and spring-latches an automatic fastening is provided, which is preferable. In order 60 that both spring-latches may be lifted at the same time in unfastening, said latches are designed to be connected by a wire or rod, R. Each section is abutted against the end of its 65 side wall, B, and is connected thereto by two or more angle-hinges H, whereof the rear branches, G, are made in angular form, to extend around the corners of the sections and engage the rear surface thereof, so as to form 70 strong braces, as indicated in the drawings.

The side walls, B, are provided with loops or eyes T near their rear ends for the attachment of the binding-chain Z, which extends across the back of the end-gate and serves as 75 a guard or check to prevent the sections from opening apart beyond the required distance, which is regulated by the length of the chain. When the chain is disconnected the gate-sections can be thrown entirely open, so as to 80 extend laterally outward at right angles to the side walls at their ends. In order to effect this the hinges are placed on the outside and the braces V are fastened at their upper ends a short distance in front of the ends of the side 85 walls, as indicated.

Having described this invention, what I claim, and desire to secure by Letters Patent, is—

1. The wagon end-gate consisting of the 90 laterally-hinged sections E F, their angle-hinges H, the overlapping perforated cross-bars I, and the catch-staples S, passing through the apertures or perforations of the cross-bars, substantially as specified. 95

2. The wagon end-gate consisting of the hinged lateral sections E F, abutting against the ends of the sides of the wagon, their angle-hinges H, the overlapping perforated cross-bars I, spring-latches N, and the notched sta- 100

ples S, passing through the apertures or perforations of the cross-bars, substantially as specified.

3. The combination, with the sectional laterally-hinged end-gate E F, the overlapping cross-bars I, and the loops or eyes T on the sides of the wagon, of the adjustable binding-chain Z, attached to said loops or eyes and extending around the sections of the end-gate 10 transversely, substantially as specified.

In testimony that I claim the above I have hereunto subscribed my name in the presence of two witnesses.

PETER YOUNG.

Witnesses:

JAMES BENNETT,
E. O. BENNETT.
